UNITED STATES PATENT OFFICE

167,787

CLOCK

Florence C. Witmer, New York, N. Y.

Application February 14, 1952, Serial No. 18,520

Term of patent 14 years

(Cl. D42—7)

To all whom it may concern:

Be it known that I, Florence C. Witmer, a citizen of the United States, residing at 651 West 188 Street, New York, county of New York and State of New York, have invented a new, original, and ornamental Design for a Clock, of which the following is a specification, reference being had to the accompanying drawing, forming a part hereof.

Fig. 1 is a front elevational view of a clock, showing my new design;

Fig. 2 is a rear elevational view; and

Fig. 3 is a side elevational view.

I claim:

The ornamental design for a clock, substantially as shown.

FLORENCE C. WITMER.
